Primary Examiner — Karen S Acker*Assistant Examiner* — Elizabeth S Ko(74) *Attorney, Agent, or Firm* — Goldstein Law Offices, P.C.(57) **CLAIM**

The ornamental design for an underground plumbing target, as shown and described.

DESCRIPTION

FIG. 1 is a perspective view of an underground plumbing target;

FIG. 2 is a front elevational view of the underground plumbing target.

FIG. 3 is a rear elevational view thereof.

FIG. 4 is a top plan view thereof.

FIG. 5 is a bottom plan view thereof.

FIG. 6 is a left side elevational view thereof; and,

FIG. 7 is a right side elevational view thereof.

1 Claim, 4 Drawing Sheets(56)
